J. E. EHRET

COMBINATION SOAP TRAY

Filed Oct. 6, 1924

INVENTOR.

JOHN E. EHRET.

BY

Harry C. Schroeder
ATTORNEYS.

UNITED STATES PATENT OFFICE.

JOHN E. EHRET, OF BERKELEY, CALIFORNIA.

DESIGN FOR COMBINATION SOAP TRAY.

Application filed October 6, 1924. Serial No. 10,975. Term of patent 3½ years.

To all whom it may concern:

Be it known that JOHN E. EHRET, a citizen of the United States, residing at Berkeley, in the county of Alameda and State of California, has invented a new, original, and ornamental Design for Combination Soap Trays, of which the following is a specification.

The figure is a perspective view of a combination soap tray, showing my new design.

I claim:

The ornamental design for combination soap tray, as shown.

In testimony whereof I affix my signature.

JOHN E. EHRET.
